UNITED STATES PATENT OFFICE.

LOUIS KIRSCH, OF NICKTOWN, PENNSYLVANIA.

ASBESTOS-SHEET CUTTER.

Application filed June 23, 1931. Serial No. 479,825.

To all whom it may concern:

Be it known that I, LOUIS KIRSCH, a citizen of the United States, residing at Nicktown, in the county of Cambria, State 5 of Pennsylvania, have invented certain new and useful Improvements in Asbestos-Sheet Cutters; and I do hereby declare the following to be a full, clear, and exact description of the invention, such as will enable 10 others skilled in the art to which it appertains to make and use the same.

This invention relates to new and useful improvements in cutting machines and particularly to machines for cutting sheets of 15 asbestos.

One object of the invention is to provide a device of this character which is simple in construction, easy and effective in operation, and which light in weight, thus enabling 20 the user to readily carry the same to a roof for the purpose of cutting asbestos shingles.

Another object is to provide a device of the character named having means for adjusting 25 the cutting blades toward and away from each other.

Another object is to provide means for supporting the asbestos sheet while being cut, and also means to catch the piece cut 30 from the sheet.

Other objects and advantages will be apparent from the following description when taken in connection with the accompanying drawing.

35 In the drawing:

Figure 1 is a side elevation of a cutting machine made in accordance with the invention, viewed from the higher table side thereof.

40 Figure 2 is a side elevation view from the opposite side of the machine.

Figure 3 is a vertical transverse central sectional view taken on the line 3-3 of Figure 1.

45 Figure 4 is an end view of the machine.

Referring particularly to the accompanying drawing, 10 represents a pair of uprights each having supporting feet 11. Secured to one vertical face of each upright 50 is a vertical elongated block 12, and also secured to the said faces of the uprights, and extending therebetween, but below the lower ends of the vertical blocks, is the stationary cutter blade 14. The blade 14 is 55 tapered from the center toward its ends whereby to strengthen the blade. Secured

to the outer face of each end of the stationary blade 14 is a small block 15, and disposed against the outer face of each of the blocks 15, and extending vertically in 60 parallel relation to the block 12, is a guide strip 16, a pivot pin 17 being disposed through the upper end of each block 12, the upright, and the upper end of the strip 16. On each of these pivot pins is mounted a 65 vertical swinging arm 18. The lower portion of each of the arms 18 is wider than the upper end, to permit the pivotally connecting thereto, of the short link 19.

Extending between the upper ends of the 70 uprights is a connecting bar 20, and pivotally mounted on this bar is the angle lever 21. Pivotally connecting the upper end of one of the arms 18 with the lower end of the angle lever 21, is a link 22, and similarly connecting the upper end of the other arm 18 with the lever, above its pivotal mounting on the bar 20, is a second link 23. Secured to the outer face of the stationary blade 14, and extending longitudinally thereof, adjacent 75 the upper edge of the blade, is a brace bar 24, and secured on the upper face of the bar 24, and extending horizontally outward therefrom, is the table 25, on which the asbestos sheet is placed for cutting. Secured to the lower portion of the other face of the blade 14, and in a plane below that of the table 25, is the receiving 80 table 26, for catching and supporting the piece cut from the sheet. 90

The movable blade 27 extends longitudinally over the blade 14 in position to cooperate with the upper edge of the blade 14, when reciprocated. The ends of the blade 27 are disposed for vertical slidable movement between the blocks 12 and the strips 16, and have the lower ends of the links 19 pivotally connected thereto. A brace bar 27' is secured to the blade 27. 95

Thus, when the lever 21, which has a 100 hand grip 21', on its other arm, is thrown upwardly, the links 22 and 23 will be pushed outwardly toward the ends of the machine, with the result that the arms 18 will be rocked on their pivots and the blade 105 27 lifted above the blade 14, by the short links 19. The asbestos sheet is placed on the table 25 and slipped under the blade 27, to the proper distance, when the operator swings the lever 21 down, causing the 110 blade 27 to cooperate with the blade 14, and sever the desired piece from the sheet.

The piece thus severed falls onto the lower table 26, as will be apparent from the drawing.

What is claimed is:

- 5 An asbestos sheet cutting machine including supports, a stationary cutting blade secured to said supports, a movable cutting blade, guides for the movable cutting blade, connection between the upper ends of
- 10 the supports, an angle lever pivotally mounted upon said connection, arms having portions of their lower ends pivotally

secured between the guide members, links connecting the other portions of the lower ends of said arms with the movable blade, 15 and pivotal connections between the upper ends of the arms and the angle lever.

In testimony whereof, I affix my signature, in the presence of two witnesses.

LOUIS KIRSCH.

Witnesses:

JOHN J. BERRY,
A. S. KIRSCH.
